UNITED STATES PATENT OFFICE.

JAMES A. JONES AND WALTER H. GILL, OF WARD, WEST VIRGINIA, ASSIGNEES OF ONE-FOURTH TO HENRY A. GRANT, OF RAVENSWOOD, WEST VIRGINIA, AND ONE-FOURTH TO JOHN A. QUICK, OF CEDARGROVE, WEST VIRGINIA.

RAILWAY-RAIL JOINT.

No. 927,411.

Specification of Letters Patent.

Patented July 6, 1909.

Application filed August 10, 1908. Serial No. 447,888.

To all whom it may concern:

Be it known that we, JAMES A. JONES and WALTER H. GILL, citizens of the United States, residing at Ward, in the county of 5 Kanawha, State of West Virginia, have invented certain new and useful Improvements in Railway-Rail Joints; and we do hereby declare the following to be a full, clear, and exact description of the invention, such as will 10 enable others skilled in the art to which it appertains to make and use the same.

This invention relates to railway rail joints and has for one of its objects to improve the construction and increase the strength and 15 utility of devices of this character.

Another object of the invention is to provide a simply constructed joint which will dispense with the necessity for employing clamp bolts or other like fastening means 20 and whereby the joint may be tightened in event of wear or working loose.

With these and other objects in view the invention consists in a chair having a rail plate integral therewith at one side and a 25 spaced longitudinal stop rib on the other side, the inner edge of the rib overhanging the chair and likewise inclined to the longitudinal plane of the chair, a detachable rail plate bearing upon the body of the chair and 30 with its outer edge inclined vertically and substantially parallel vertically to the overhanging portion of the stop rib and with a lip bearing over the stop rib, and a wedge key having vertical inclined sides to correspond 35 to and bear against the vertical inclined sides of the stop rib and of the detachable rail plate.

The invention further consists in certain novel features of construction as hereafter 40 shown and described and then specifically pointed out in the claims, and in the drawings illustrating the preferred embodiment of the invention, Figure 1 is a side elevation of the improved device applied. Fig. 2 is a 45 plan view of the same. Fig. 3 is a transverse section on the line 3—3 of Fig. 2. Fig. 4 is a plan view of the chair with the parts detached. Fig. 5 is a perspective view of the wedge key, detached.

50 The improved device comprises a base member or chair 10 of sufficient length to bear over two or more ties and with an integral rail plate 11 at one side and a stop rib 12 at the other side, the stop rib spaced for a

considerable distance from the integral rail 55 plate and with its inner edge at an angle to the longitudinal plane of the chair and its integral rail plate 11, as shown.

Bearing upon the chair between the integral rail plate 11 and the stop rib 12 is a detachable rail plate 13 having its outer edge inclined vertically and substantially parallel to the inclined edge of the stop rib and with a lip 14 bearing over the stop rib. Fitting between the inclined edges of the stop rib and 60 of the detachable rail plate is a wedge key 15 having its side edges inclined to correspond with and to engage against the inclined edges 65 of the stop rib and of the detachable rail plate. 70

The confronting ends of two rails are represented respectively at 16—17 and provided with the usual transverse clamp bolt holes indicated at 18—19, and the detachable rail plate 13 is provided with spaced studs 20 75 fitting into these bolt holes when the rail plate is disposed in a position against the rail ends, as shown. When the rail plates are disposed in position the wedge key 15 is driven into its seat and firmly locks the parts 80 and supports them against displacement caused by the severe impact of the passing trains, and in the event of the development of any looseness between the parts a blow upon the wedge key will take up any slack 85 which may thus occur. By this means the joint may be kept tight and all rattling and looseness prevented.

The upper base of the face 10 is provided near one end with spaced recesses 21 and the wedge key 15 is formed with its larger end thickened vertically as at 22 to enter these notches consecutively as the key is driven "home", and thus lock the key in position. The plurality of recesses also enable any 90 looseness to be taken up by driving the key farther into its seat until the thickened end enters another recess, as will be obvious. The lip portion 14 of the plate 13 next to the larger end of the wedge key is cut away as 95 shown at 23 to expose the upper face of the larger end of the wedge key to permit an implement to be applied to elevate the same to assist in its removal if for any reason the joint is to be dismembered or parts removed. 100 Thus the improved device may be readily detached from the rails if required.

The chair together with its rail plate 11

and rib 12 will be in one single piece preferably of pressed or cast steel, while the detachable rail plate 13 and its lip 14 will be likewise in one single piece of pressed, rolled or cast metal, preferably steel, while the wedge key 15 will preferably be of hardened steel.

The improved device is simple in construction, can be inexpensively manufactured and applied and will effectually hold the rails without the necessity for employing clamp bolts or other parts which are liable to become loose under the severe strains to which devices of this character are subjected. This improved device may be applied to rails already in use, and the bolt holes utilized to receive the pins 20, so that the rails may be used in the condition in which they are found. A recess 24 is preferably formed in the thickened end of the key 15, to receive a releasing implement.

What is claimed, is:—

1. A railway rail joint comprising a chair having a uniform upper surface and with an integral rail plate at one side of the uniform surface and a stop rib at the other side of the uniform surface, said stop rib having its inner face overhanging and inclined to the longitudinal plane of the same, a detachable rail plate at the opposite side from the integral rail plate and with its lower face bearing upon the uniform surface of the chair and its outer edge inclined to the perpendicular and substantially parallel to the vertical plane of the overhanging portion of the stop rib, and with a lip extending over the stop rib, and a wedge key bearing upon the chair between the inclined edges of the stop rib and the detachable rail plate and with its side edges inclined to correspond therewith.

2. The combination with the confronting ends of two railway rails having spaced apertures in their vertical webs, of a rail joint comprising a chair having a uniform upper

surface and with an integral rail plate at one side of the uniform surface and a stop rib at the other side of the uniform surface, said stop rib having its inner face overhanging and inclined to the longitudinal plane of the chair, a detachable rail plate having spaced studs engaging in said rail apertures and with its lower face bearing upon the body of the chair and its outer edge inclined to the perpendicular and substantially parallel to the vertical plane of the overhanging portion of the stop rib and with a lip extending over the stop rib, a wedge key bearing upon the chair between the inclined edges of the stop rib and of the detachable rail plate and with its side edges inclined to correspond therewith.

3. A railway rail joint comprising a chair having an integral rail plate and a stop rib spaced therefrom at the other side, said stop rib having its inner face overhanging the chair and inclined to the longitudinal plane of the same and said chair having a plurality of spaced recesses annexed to the stop rib, a detachable rail plate at the opposite side from the integral rail plate and with its lower face bearing upon the body of the chair and its outer edge inclined to the perpendicular and substantially parallel to the vertical plane of the overhanging portion of the stop rib, and with a lip extending over the stop rib, and a wedge key bearing upon the chair between the inclined edges of the stop rib and the detachable rail plate and with its side edges inclined to correspond therewith and with the larger end thickened to engage in said recesses.

In testimony whereof, we affix our signatures, in presence of two witnesses.

JAMES A. JONES.
WALTER H. GILL.
